UNITED STATES PATENT OFFICE.

EDGAR B. SYMONS, OF LOS ANGELES, CALIFORNIA, ASSIGNOR TO SYMONS BROTHERS COMPANY, OF MILWAUKEE, WISCONSIN, A CORPORATION OF SOUTH DAKOTA.

CRUSHING DISK.

Application filed January 24, 1925. Serial No. 4,375.

My invention relates to an improvement in crushing disks and particularly to an improvement in disks employed in disk crushers wherein the material to be crushed is delivered into a substantially lenticular crushing zone bounded by opposed crushing disks of which at least one is cup-shaped or concave.

One object is to provide such a disk which shall be easily removable and replaceable. Another object is the provision of a disk formed of a plurality of sections, so that that section which wears out most rapidly may be replaced without throwing away the less rapidly wearing sections of the disk. Another object is to provide a disk in which the deformative effect of the stresses about the center of the disk, attendant upon securing it to the crushing machine, and the pressures directed against its outer edge, are reduced to a minimum. Another object is to provide disk sections which are interchangeably usable upon either of the two opposed disk supporting heads. Other objects will appear from time to time in the course of the specification and claims.

I illustrate my invention more or less diagrammatically in the accompanying drawings wherein

Figure 1 is a section through the crushing head of a machine supplied with my type of disks;

Figure 2 is a similar section showing a modified form of disk and securing means;

Figure 3 is a detail section on an enlarged scale of a variant form of securing means; and

Figure 4 is a diagrammatic view of the stresses and strains to which such a disk is exposed in the course of the normal operation of the crusher.

Like parts are indicated by like symbols throughout the specification and drawings.

The operating, driving and controlling parts of my crushing machine have been omitted from the drawings since they form no part of my invention.

A is a hollow shaft adapted to be rotated from a power source not herein shown and B is a solid shaft, within the hollow shaft but inclined to it, also adapted for rotation. Mounted at the extremity of the shaft A is the socket member A¹ having the spherical bearing surface A² and terminating in the outwardly projecting flange A³.

Secured to the end of the shaft B is the member B¹ having a spherical bearing surface B² provided for example with a spherical babbiting B³. B⁴ is a circumferential outwardly projecting flange, the entire element having the conic concave bearing surface B⁵ adapted to support the crushing disk member C. C¹ is any suitable disk engaging washer, or inner disk member, adapted to be secured, for example by means of the bolt C², to the end of the shaft B and thus to hold the disk member C in position on the ball member B¹. C³ C⁴ are pins driven into the apertures in the washer or disk member C¹ adapted to receive the upstanding heads of said pins C³.

Positioned against the outer ledge or corner D of the flange A³ is the ring member D¹ which has the inwardly projecting flange D² adapted to limit the inward movement of the ring member toward the crushing zone. The ring D¹ is provided with outwardly projecting spring abutments D³ upon which the spiral springs D⁴ are mounted in pairs about the circumference of the ring. D⁵ is an angle member, the inner edge of which abuts against the inner corner of the flange A³. It is apertured to permit the passage of the holding bolts E about which are spacing sleeves E¹ compressed between the angle element D⁵ and the circumferential ring E². E³ are removable spacing shims.

Adapted to be held by the bolts E is the centrally apertured disk supporting member G, on which is mounted the outer disk member G¹, which may be held in position for example by the outwardly screw threaded locking ring G² and the inwardly locking screw threaded ring G³. The head G is provided with an outwardly projecting flange or flanges G⁵ through which pass the bolts E.

G⁶ are lugs on the ring G³ whereby the ring G³ may be rotated in relation to the ring G², or may be held against rotation when the ring G² is rotated. G⁷ are pockets in the ring G² wherein a wrench may be inserted to prevent its rotation when the ring G³ is being rotated.

In the structure as shown in Figure 2 H is a hollow main shaft rotatably mounted in the bearings H¹. It is flanged as at H², the flange containing the spherical bearing H³, in which is rotatably and oscillatably mounted a bearing head or ball H⁴ which supports the later described crushing disk and which

is carried upon a shaft H^6 contained within the hollow shaft H . H^7 is any suitable hood mounted upon the frame member H^8 , which frame also supports the bearing H^1 . The hood is adapted to catch the discharge from the crushing head.

I is an annular centrally apertured disk supporting plate. Penetrating such central aperture is the chute I^1 which discharges into the lenticular crushing zone between the opposed disks. The plate I is provided with a peripheral shoulder portion K^1 which is perforated in opposition to perforations in the flange H^2 , said perforations being penetrated by the bolts I^3 upon which are mounted any suitable spacing members I^4 . The bolts are spaced comparatively close together and they rigidly tie together the flange H^2 and the supporting plate I . It will be observed that the plate I is provided with a forward bearing surface I^5 which is inwardly cupped or concave toward the central aperture of the plate. About the outer periphery of the plate, and upon this bearing surface, is seated the disk element K which is provided with an outer bearing ring I^2 about its outer edge and an inner bearing ring K^2 about its inner edge. The inner periphery of the element K terminates in an inclined or reduced portion K^7 shaped preferably as shown in Figure 1, although many changes may be made in the specific form employed.

Positioned on the plate I within the disk member K is the inner disk member L , its outer edge L^1 inclined or tapered or shaped to overlie and to conform to the inner reduced portion K^7 of the outer disk element K . Its inner edge is inclined or beveled or reduced as at L^2 .

Positioned in the central aperture of the plate L is the securing sleeve or hollow plug M which is provided at its inner end with an outwardly projected circumferential flange M^1 overlying and conforming to the reduced inner edge L^2 of the disk element L . The opposed end of the block M is outwardly screw-threaded as at M^2 in mesh with a securing ring M^3 which is adapted, when rotated, to be seated against the annular bearing surface M^4 , about the central aperture of the plate I and to draw the disk firmly against the plate.

The disk elements K and L may be provided with holding lugs O adapted to prevent their rotation in relation to the plate I by their penetration into apertures or sockets O^1 in its surface.

The head H^4 is provided with a concave, conical bearing surface P , about the outer edge of which is positioned an outer disk element R , preferably identical with the opposed outer disk element K .

Positioned within it against the surface P is an inner disk S , the outer edge of which

overlies and conforms to the inclined inner edge of the disk member R . It is held in position by any suitable central block or securing screw S^1 the details of which form no part of the present invention.

70

Figure 3 illustrates a slight variation in the securing means. The plug or sleeve M is provided with the relatively extensive outwardly projecting flange M^{10} . In order to prevent rotation of the sleeve M during rotation of the lock ring M^2 in mesh with it, I provide a keyway M^{11} adapted to receive a key M^{12} which locks the sleeve M against rotation with the plate I .

It will be realized that while I have illustrated an operative device, nevertheless many changes might be made in the size, shape, number and disposition of parts without departing from the spirit of my invention and that I wish my description and drawings to be taken as in a broad sense illustrative, rather than as limiting me to the specific structure described and shown.

The use and operation of my invention are as follows:

My invention relates to crushing disks of generally concave or dish-shaped type, which bound a lenticular crushing chamber. In general practice these disks are manufactured from manganese steel, which while extremely hard has the characteristic of flowing or deforming under pressure. When a single piece disk is employed, the tendency of the manganese to flow or stretch about the outer edge of the disk prevailingly causes distortion of the disk and a very heavy strain upon the inner edge of the disk and the securing means whereby it is secured to the supporting head. This tendency is diagrammatically illustrated in Figure 4 in which the two rings, a and b represent the inner and outer edges of the disks. When the outer edge of the disk stretches and expands, the diameter of the disk is enlarged to the size represented by a' . The inner edge of the disk tends to be lifted to the position shown in dotted lines, b' . The result, in practice, is the breakage of many disks, or the pulling away of the center of the disk from the centrally disposed securing means.

I dispose of this difficulty by providing a multiple ring disk, having outer and inner ring portions, the number of concentric ring members varying to suit the size of the disk and the needs of the particular use to which it is put. Obviously, since the disk as a whole is made of a plurality of annular sections, the stretching of the outer sections does not cause additional pressure about the inner periphery of the inner section, and accordingly does not distort the disk as a whole, or tend to pull the inner edge of the disk away from the securing head.

In practice the outer edges of the disks

130

are subjected to much heavier wear than the inner and are accordingly worn down much more rapidly. However, in the use of a one piece disk the whole disk must be scrapped when the outer edge is worn down, even though the inner portion is still usable. In my improved disks I am able to replace the heavily worn outer disk members more frequently than the less worn inner ones, 10 with a great resultant saving of metal.

I provide disk members which are adaptable for use with either head. Thus in Figure 2 the disk members R and K may be exchangeably used on either head, and the disk members C and G¹ in Figure 1 are identical in form. I may use single exchangeable disk members, such as C and G¹, or I may employ a plurality of exchangeable ring sections. 15

20 In shaping the multiple ring disks it is important that the joints be made relatively flat, for if the new outer ring sections, which are put in when the old ones wear out, are to be held in place by the partly worn inner rings, no shoulder must be formed which will obstruct the outward travel of the material as it is being crushed. It will be understood that by shaping the inner disk members to overlie the inner edges of the 25 outer disk members I am able to hold the outer members in place without additional securing means.

Referring to the inner disk members of the inner heads, shown to the left of Figures 1 and 2 I prefer to use the washers C¹ and S as crushing members and to form them of material as resistant to the crushing impact as the outer disk members themselves. Similarly, I employ the forward 30 faces of the sleeves M and G² as part of the crushing disk and must therefore make them of as hard material as the rest of the disk. Since the rear of the sleeve has to be screw-threaded I may heat-treat or otherwise harden the crushing face of the sleeve, 35 without hardening the rear of the rest of the sleeve. As an alternative I may, as shown in Figure 2, employ a sleeve of manganese steel or similar hard material about 40 which is positioned the screw-threaded collar M² of softer material. For example the soft collar may be set in the mould, and the manganese portion subsequently poured. 45

I claim:

50 1. The combination with a crushing disk for use with disk crushing machines, of a securing sleeve having a forward crushing face conforming to and continuous with that of the disk, the outer edge of the securing sleeve being adapted to overlie the inner edge of the disk, said sleeve being of material of substantially the same hardness as the disk, and a body of softer material associated with the rear portion of said sleeve. 55

2. The combination with a crushing disk

for use with disk crushing machines, of a securing sleeve having a forward face conforming to and continuous with that of the disk, the outer edge of the securing sleeve being adapted to overlie the inner edge of the disk, the forward crushing face of the sleeve being formed of material substantially harder than that of the rear portion of the sleeve. 70

3. A crushing disk for use with disk crushing machines, comprising a plurality of concentric crushing ring sections, the outer edge of each ring being shaped to overlie the inner edge of the ring next outermost, the inner and outer surfaces of the sections being generally continuous, and means, positioned on the non-operative face of an outer crushing ring adapted, in cooperation with an inner crushing ring, to hold said outer ring in fixed position upon the crushing head. 75

4. A crushing disk for use with disc crushing machines, comprising a plurality of concentric crushing ring sections, the outer edge of each ring being shaped to overlie the inner edge of the ring next outermost, the inner and outer surfaces of the sections being generally continuous, the outer ring section being substantially thicker than the inner ring section, and means, positioned on the non-operative face of an outer crushing ring adapted, in cooperation with an inner crushing ring, to hold said outer ring in fixed position upon the crushing head. 80

5. A crushing disk for use with disk crushing machines, comprising a plurality of concentric crushing ring sections, the inner and outer surfaces of the sections being generally continuous, the compound disk so formed increasing progressively in width from center to circumference, and means, positioned on the non-operative face of an outer crushing ring adapted, in cooperation with an inner crushing ring, to hold said outer ring in fixed position upon the crushing head. 85

6. A crushing disk for use with disk crushing machines, comprising a plurality of concentric crushing ring sections, the inner and outer surfaces of the sections being generally continuous, and means, positioned on the non-operative face of an outer crushing ring adapted, in cooperation with an inner crushing ring, to hold said outer ring in fixed position upon the crushing head, the inner of said sections being adapted to direct a holding pressure upon the inner edge of the outer section. 115

7. A crushing disk for use with disk crushing machines, comprising a plurality of eccentric crushing ring sections, the inner and outer surfaces of the sections being generally continuous, the inner of said sections being adapted to direct a holding pres- 120
125
130

sure upon the inner edge of the outer section, and additional means, positioned on the non-operative face of the outer section, adapted, in cooperation with such holding pressure of the inner section, to hold the outer section in fixed position on the crushing head.

8. A crushing disk for use with disk crushing machines, comprising a plurality of concentric crushing ring sections, the inner and outer surfaces of the sections being generally continuous, the inner of said sections being adapted to constrain the outer to fixed position upon the crushing machine, and rotation preventing rearwardly projecting lugs associated with said sections.

9. A crushing disk for use with disk crushing machines, comprising a plurality of concentric crushing ring sections, the inner and outer surfaces of the sections being generally continuous, the inner of said sections being adapted to constrain the outer to fixed position upon the crushing machine, and rotation preventing rearwardly projecting lugs associated with the outer of said sections.

10. A concave crushing disk for use with a disk crushing machine having opposed concave crushing heads, comprising a plurality of concentric ring sections, the outer and inner surface of said ring sections being generally continuous, the inner being adapted to constrain the outer in position upon the crushing head.

11. A concave crushing disk for use with a disk crushing machine having opposed concave crushing heads, comprising a plurality of concentric ring sections, the outer and inner surface of said ring sections being gen-

erally continuous, the inner being adapted to constrain the outer in position upon the crushing head, the compound disk so formed increasing in thickness from the center outwardly.

12. A concave crushing disk for use with a disk crushing machine, such disk being bounded by a concave forward crushing face and a convex rear supporting face, and comprising a plurality of concentric crushing ring sections, the inner and outer surfaces of the sections being generally continuous.

13. A concave crushing disk for use with a disk crushing machine, such disk being bounded by a concave forward crushing face and a convex rear supporting face, and comprising a plurality of concentric crushing ring sections, the inner and outer surfaces of the sections being generally continuous, the outer edge of each ring being shaped to overlie the inner edge of the ring next outermost.

14. A concave crushing disk for use with a disk crushing machine, such disk being bounded by a concave forward crushing face and a convex rear supporting face, and comprising a plurality of concentric crushing ring sections, the inner and outer surfaces of the sections being generally continuous, the outer edge of each ring being shaped to overlie the inner edge of the ring next outermost, and rotation preventing lugs rearwardly projecting from the rear faces of the outer sections.

Signed at Los Angeles, county of Los Angeles and State of California, this 15 day of January 1925.

EDGAR B. SYMONS.
